UNITED STATES PATENT OFFICE.

ELIHU THOMSON, OF SWAMPSCOTT, MASSACHUSETTS, ASSIGNOR TO THE THOMSON-HOUSTON ELECTRIC COMPANY, OF CONNECTICUT.

ELECTRIC-LIGHTING SYSTEM.

SPECIFICATION forming part of Letters Patent No. 508,647, dated November 14, 1893.

Application filed August 12, 1891. Serial No. 402,429. (No model.)

To all whom it may concern:

Be it known that I, ELIHU THOMSON, a citizen of the United States, residing at Swampscott, county of Essex, and State of Massachusetts, have invented a certain new and useful Improvement in Electric-Lighting Apparatus, of which the following is a specification.

The present invention relates to electric lighting apparatus whereby practically continuous lighting may be obtained in isolated situations, such as small light-houses, without requiring the continued attention of an operator. It provides for the automatic replacement of electric lamps as they are used up or broken, the lamps so substituted being at the same time brought to the proper position, as for example to the center of a Fresnel lens combination for directing the rays. The broken lamp is thus replaced both as to circuit connection and as to position.

My invention is, therefore, applicable to the maintaining of a light at various points in a harbor, and for prolonged periods of time without attention. It may also be applied to providing light on buoys floating or anchored in stations where it is required to give warning to vessels.

In the accompanying drawings Figure 1 is a vertical sectional view of a lighting apparatus embodying my invention. Figs. 2 and 3 show the lamp. Fig. 4 shows a modification of the lamp replacing means. Fig. 5 is a diagram of the system. Fig. 6 shows an indicator for showing the number of lamps re-

placed, and Fig. 7 shows a detail.

Fig. 1 shows at P a pedestal or tubular support surmounted by a Fresnel lens combination, L, L, from which light is emitted and which is suitably capped at the top by a removable cap, allowing access to the interior. In the center is a guide composed of vertical rods g, g, there being say, three or four placed so as to support a series or row of globular lamps a, b, c, in between them and allowing only a vertical motion to the same. Of these lamps, the bottom one a, is secured to a rod Q, having a plunger or weight W attached to its lower end. This plunger or weight fits loosely in a tube or cylinder T in which it may move downward. The cylinder T is fixed in position

and filled with sand or such like material, and is provided with a valve at the lower end which allows the sand to run out when the magnet M, suitably provided, is acted upon to open the same. This magnet M is shown in shunt to the connections or mains m, n, and such mains run to fixed contact pieces e, f against which the terminals of the lamp a, respectively bear when the lamp is in the position shown with its light giving part at the focal center of the lens system L, L. Now, the magnet M being properly adjusted, it remains inactive so far as the opening of the valve is concerned until the rupture of the carbon conductor in the lamp a, which rupture gives an increase of potential, which will in turn result in the operation of the magnet M in opening the valve V at the bottom of the tube T. The sand in the tube T will begin to run out and the lamp a will descend, but secured to it above is the lamp b, and again the lamp c, which also descends. The sand continues running until the terminals of the lamp b come into contact with the contact pieces e, f, provided therefor. The lamp b is thus substituted for the destroyed lamp a and the magnet M resumes its normal strength and the valve V again closes, shutting off the escape of sand. The lamp being now in focus in the lighting system, continues to burn as did the lamp a, until its destruction ensues when by a similar series of actions the lamp c is substituted for the lamp b. This may go on with as many lamps as are provided. It will be seen also that should the current cease from any cause external to the lamp the valve V will remain closed, and the magnet M not be put into operation.

In Fig. 2 the construction of each lamp is shown. The terminals t, t', are insulated and attached to the neck S' on one end of the lamp while the other end is provided with a screw socket S whereby it may be screwed into position with the preceding lamp, or screwed upon the rod Q, as the case may be.

Fig. 3 shows the terminals t, t', coming into contact with the fixed contacts e, f, as when the substitution is to be made of one lamp for the other. The pieces e, f, should have enough springiness or yield not to hamper the motions of the lamp in its motion down-

ward or the terminals t, t , of the lamp itself may be yielding or springy for the same purpose, as shown in Fig. 2.

Fig. 4 shows the magnet M in series with the lamp a and acting by its attraction on an armature N to hold closed the valve V. This arrangement would be adapted to work only in case the lamp a was on a circuit of such low potential as to cause rupture of that circuit on the breakage of the lamp, or to cause a release of the armature N, by the lamp acquiring too high a resistance and so weakening the current through it, and said arrangement has therefore the objection that the current must always be kept on in sufficient force to maintain the valve closed, as otherwise a substitution would constantly be made on stoppage of current from any cause, whether the lamp had anything to do with it or not.

Fig. 5 shows how a dynamo D in a suitable location or station may be caused to feed in multiple arc a number of lights provided with the arrangements Fig. 1, as at L, P, and L', B. L, P, represent a lamp on a pedestal and L, B a buoy anchored. A well armored cable is used to convey the currents in each case.

It is desirable to provide at the generating station an indicator or indicators I, I' for recording the number of shifts which have been made automatically by the opening and closing of the valve V and the substitution of one lamp for another. The construction of such an indicator may be varied in many ways. Fig. 6 shows one form. In this case a differential magnet system is provided in combination with the wires m, n, going to the lamp. An armature lever L is provided with a pawl p, which acts upon a ratchet r and sets a needle over a scale Z, so as to indicate the number of times the armature lever has been moved. The ratchet r may be arranged to move with friction so as to remain where it is placed by the pawl p. The magnet coil K is shown in shunt to the mains m, n, and therefore in shunt to the lamp fed by them, while the magnet M' is in series with the lamp. A spring v, may in addition be provided to maintain the balance between the poles of the magnets or the actions of the two coils. Under normal conditions the lever may be set to a balance. If now the lamp breaks, the magnet M will lose its power particularly if the lamp be of sufficiently low resistance, as say thirty volts, and the magnet K will acquire power whereby the action on the lever will be such that the pole is drawn to indicate a movement or shifting action, the magnet M' acquiring the power on the substitution of a lamp, as in Fig. 1, and the magnet K losing power, the lever is set back into its original position. If the currents fed through the apparatus be of an alternating character they may be fed along the lines at comparatively high potential and transformed down for use

in the lamp close to or in the vicinity of the lamp. In such case the indicator Fig. 6 would be placed in the primary mains while the lamp was run from the secondary and the valve controlling magnet M, Fig. 1, would be either in the primary or secondary as convenience dictated. While the magnet M, Fig. 1, is shown in shunt, it evidently could be differential as shown in Fig. 6 and used to operate the valve, and instead of a magnet, other well-known equivalents therefor could be used.

It is obvious that this lamp shifting or replacing device may be applied to any light directive apparatus, as well as to the lens system shown.

What I claim as new, and desire to secure by Letters Patent, is—

1. The combination with a vertically gravitating carrier, of two or more lamps mounted thereon one above the other, fixed contacts with which said lamps may successively engage, and means for automatically arresting the fall of the carrier when the circuit becomes closed through a lamp.

2. The combination with a vertically gravitating carrier, of two or more lamps mounted thereon one above the other, fixed contacts with which said lamps may successively engage, means for automatically releasing the carrier when the circuit is broken, and means for automatically arresting the carrier when the circuit becomes closed again.

3. The combination with a vertically gravitating carrier, of two or more lamps mounted thereon one above the other, fixed contacts with which said lamps may successively engage, and an electro magnet in circuit with said contacts and automatically controlling the vertical movement of the carrier.

4. The combination of the vertical gravitating carrier, two or more lamps mounted thereon one above another, and detaining and releasing devices for said carrier.

5. The combination with two or more lamps mounted one above the other on a gravitating carrier, of a shifting device for said carrier comprising a plunger, a cylinder in which the plunger works, containing sand or similar material, and a valve controlling escape of such material, substantially as described.

6. The combination with two or more lamps mounted one above the other on a gravitating carrier, of the electro-magnet in shunt with the lamp circuit, the valve controlled by said magnet, the cylinder containing sand and having an aperture controlled by said valve, and the plunger working in said cylinder and connected to said carrier, substantially as set forth.

7. The combination in an electric lighting apparatus of a vertical series of lamps attached end to end, each lamp having at its opposite ends attaching devices of different but corresponding character, so as to engage

with the corresponding ends of adjacent lamps, and means for moving said series vertically.

8. An electric lighting system comprising a generating station, a circuit leading therefrom to fixed terminals, two or more lamps movably mounted to come into successive connection with such terminals, a current controlled device shifting said lamps into successive connection and responsive to va-

riations in the current through the lamp, and a current responsive device at the generating station controlling an indicator or counter.

In witness whereof I have hereunto set my hand this 5th day of August, 1891.

ELIHU THOMSON.
